M. LENKE.
CARGO BEAM.
APPLICATION FILED AUG. 25, 1916.

1,228,120.

Patented May 29, 1917.

Inventor
Melchior Lenke
By his Attorney
E. W. Marshall

UNITED STATES PATENT OFFICE.

MELCHIOR LENKE, OF BROOKLYN, NEW YORK.

CARGO-BEAM.

1,228,120.

Specification of Letters Patent. Patented May 29, 1917.

Application filed August 25, 1916. Serial No. 116,788.

To all whom it may concern:

Be it known that I, MELCHIOR LENKE, a citizen of the United States of America, and a resident of Brooklyn, Kings county, and 5 State of New York, have invented certain new and useful Improvements in Cargo-Beams, of which the following is a specification, reference being had to the accompanying drawings, forming a part thereof.

10 My invention relates to improvements in cargo beams for pier sheds, warehouses and the like, and its object is to improve upon that part of such structures as is provided for the support of overhead tackle blocks. 15 More specifically, its object is to provide plates of material depth and a pivotal support for such plates to take the place of the heavy rigid structures heretofore used as cargo beams.

20 In order that my invention may be thoroughly understood, I will now proceed to describe the same in the following specification, and then point out the novel features thereof in appended claims.

25 Referring to the drawings:

Figure 1 is a sectional end view of a part of a pier shed with its cargo beam made in accordance with my invention.

Fig. 2 is a front elevation of my improved 30 cargo beams and their supports.

Fig. 3 is an end elevation on a larger scale, of a part of that part of a pier shed structure which supports the cargo beam with the beam itself shown in section.

35 Fig. 4 is a front elevation partly in section on a still larger scale of the end portions of two of my improved cargo beams and their supporting parts.

Like characters of reference designate corresponding parts in all the figures.

40 10 designates a part of a pier shed of standard construction; 11 designates the vertical posts which form a part of such structures. These, according to usual practice, 45 form the side posts of door openings and are carried up above the roof of the shed a considerable distance for the purpose of supporting that part of the structure which is known as the cargo beam. 12 is one of the 50 usual braces for these posts 11. It is common to provide a walk 13 near the upper end of the posts, protected by a hand rail 14.

55 The usual practice has been to use rigid girders between the posts 11 near their upper ends, as cargo beams or overhead supports for tackle blocks used in moving

freight into or out of the shed between the posts 11. On account of the fact that strains are applied to these cargo beams from points away from the shed, as for example, when unloading a ship or barge in the position indicated by broken lines at 15, these beams have to be capable of withstanding considerable lateral strains and consequently have had to be made very heavy.

60 According to my present invention I use a plate or I-beam 20, of material width, and provide it with pivotal or swinging supports at its ends. To this end I provide transverse hanger plates 21 secured to the 65 ends of the beams 20 by angle brackets 22. Above the beams 20 these hanger plates are 70 perforated to fit over turned steel pivot fittings 23 on which they swing freely.

16 are supporting plates affixed to the 75 upper ends of the posts 11 by suitable angle brackets 17. The pivot fittings are secured to these supporting plates by through bolts 18 and rivets 19.

Secured to the beams 20 at spaced intervals 80 are stirrups 24 which pass over the lower flange and are riveted to the web thereof as at 25.

In use the hook of a tackle block 30 is supported in one of these stirrups. A hoisting 85 cable 31 from a suitable hoisting engine, not shown, is carried under a sheave 32, up over the tackle block 30 and down as at 33 to the freight or cargo in vessel at 15. The distance of the cable at 33 away from the

90 vertical plane through the cargo beam will cause the latter to swing at an angle which corresponds with the resultant of the forces applied through the hoisting cable as shown in Fig. 1. Therefore, the whole 95

depth of the cargo beam is made available to resist the strains put upon it, and because of its change of position it receives no lateral or bending strains. It has been shown in actual structures that by this invention 100 the weight of heavy cargo beams capable of withstanding these lateral or bending strains is dispensed with, thereby making the structure much lighter at a part where weight is decidedly undesirable. At the 105 same time the cost of the structure is materially reduced, and a better and more efficient cargo beam provided.

110 The structure shown and described is the form in which I have embodied my invention in large pier sheds, but I do not intend to limit the invention to this particular

kind of structure nor to the exact details of construction, and in fact intend no limitations other than those imposed in the appended claims.

5 What I claim is:

1. A permanent rigid structure constructed with upright posts spaced a material distance apart, a cargo beam of greater depth than thickness provided with means near the lower edges of said beam for connecting a tackle block therewith, and pivotal supports at the ends of said beam at higher points than said connecting means, said supports being connected with said posts.
- 10 2. A permanent rigid structure constructed with upright posts spaced a material distance apart, a cargo beam comprising a longitudinal I-beam, a stirrup passing over the lower flange of the I-beam and affixed to the web thereof, transverse hanger plates secured to the ends of said I-beam, and pivotal supports for the hanger plates above the upper flange of the I-beam and connected with said posts.
- 15 3. A shed structure comprising spaced upright posts adapted to form the sides of the

door opening, a cargo beam between said posts comprising a longitudinal horizontally disposed plate, stirrups affixed thereto at spaced intervals over the door opening and 30 projecting below the lower edge of said plate, transverse hanger plates secured to the ends of the longitudinal plate, and pivotal supports for the hanger plates above the upper edge of the longitudinal plate 35 near the upper end of said upright posts.

4. A shed structure comprising spaced upright posts adapted to form the sides of a door opening, a cargo beam between said posts comprising a longitudinal horizontally 40 disposed I-beam, a plurality of stirrups at spaced intervals over the door opening passing over the lower flange of the I-beam and affixed to the web thereof, transverse hanger plates secured to the ends of said I-beam, and pivotal supports for the hanger plates above the upper flange of the I-beam, near the upper end of said upright posts.

In witness whereof, I have hereunto set my hand this 24th day of August, 1916.

MELCHIOR LENKE.
